Specification for Design.

Patented May 13, 1913.

Application filed February 15, 1910. Serial No. 544,135. Term of patent 7 years.

To all whom it may concern:

Be it known that I, ORESTE E. S. AZZONI, subject of the King of Italy, and resident of Philadelphia, in the county of Philadelphia and State of Pennsylvania, have invented a certain new, original, and ornamental Design for a Statuette, of which the following is a specification, reference being had to the accompanying drawing, forming part thereof, and wherein—

What I claim as new is:

The ornamental design for a statuette as shown.

ORESTE E. S. AZZONI.
